UNITED STATES PATENT OFFICE.

PATRICK JOSEPH GRIFFIN, OF ANNISTON, ALABAMA.

FURNACE-ROOF.

1,274,034.

Specification of Letters Patent. Patented July 30, 1918.

Application filed February 24, 1917. Serial No. 150,695.

To all whom it may concern:

Be it known that I, PATRICK JOSEPH GRIFFIN, a citizen of the United States, and resident of Anniston, in the county of Calhoun and State of Alabama, have invented certain new and useful Improvements in Furnace-Roofs, of which the following is a specification.

My invention relates to metallurgical furnaces and has particular reference to a novel roof adapted for use in connection therewith.

It is well known that owing to the intense heat, particularly in electric furnaces, the roof structure is likely to cause considerable trouble and consequently to delay the operations and reduce the efficiency of the plant. An object of the present invention is to so construct and arrange the elements going to make up the roof structure that a roof may be built apart from the furnace and, when occasion requires, be removed bodily and placed in position over the furnace following the removal of the defective roof. The desired result is accomplished by constructing the roof in the form of a stable dome, in the case of a round furnace, or in the form of an arch in the case of a square or otherwise shaped furnace. I secure the desired results by providing a metallic ring in the case of the circular roof, the ring acting as a support for skew bricks. Concentric rows of tapered bricks are associated with the skew bricks, a keystone brick completing the dome.

A roof of this description is adapted to be built over a form and entirely completed at a point apart from the furnace. This facilitates operations in many particulars as the roof may be built at leisure at a point removed from the heat of the furnace. In event of the failure of the roof on the furnace it may be removed and the new roof replaced thereon without waiting for the furnace to cool down, as would be necessary in event extensive repairs were to be made.

Roofs for use in connection with electric furnaces are commonly composed of silica brick, and as this material has a relatively high coefficient of expansion provision must be made therefor. To this end it is common to insert thin strips of wood or similar non-refractory material. When the roof becomes highly heated this material is de-

stroyed and the bricks are permitted to expand.

It frequently happens, however, that certain of the expansion strips burn out before others thereof, in which case the adjacent bricks are likely to drop down a certain distance and in some cases to drop into the furnace. In event they project downwardly beyond the adjacent bricks, the projecting portion will flake and spall off. In event of the unequal location or positioning of the bricks, the arch is deprived of the capacity for equal expansion and adjacent bricks are likely to be bursted. Provision is made in my design for permitting equal expansion and contraction and preventing the loosening and dropping of any bricks following the destruction of the expansion strips. The result is secured by providing lateral ribs or projections in certain of the key bricks, which projections overlie portions of adjacent bricks thereby preventing relative vertical movement therebetween. At the same time the bricks are permitted to expand as necessary.

My improvement is important also from a safety standpoint, as it is possible by the use of my construction for operators to walk upon the roof with safety while making repairs around the electrodes.

Other objects and advantages will appear hereinafter.

The invention will be more readily understood by reference to the accompanying drawings in which:

Figure 1 is a plan view of the roof for an electric furnace constructed in accordance with my invention and,

Fig. 2 is a sectional view on the line 2-2 of Fig. 1.

The furnace, for which the roof is designed, is not shown in the drawings, it being understood, however, that it is of the conventional form employed for electric furnaces. The roof is circular in outline, the periphery or contour being defined by a heavy metallic ring 10, to which a plurality of spaced eyes 11, are riveted thereby providing means adapted to be engaged by a crane for lifting the roof as required. It will be understood that the roof is dome-shaped and is intended to be built over a suitably shaped form. In the present instance the roof is shown as comprising six

concentric rows of bricks, 12, 13, 14, 15, 16, 17, and a keystone brick 18. Suitable electrode openings 19, are shown in the roof. The bricks in the row 12, are termed skew 5 bricks and are confined between lower and upper angles 20, 21, riveted to the rings 10. The inner face of the skew bricks is inclined and stepped, the recess 22, near the upper edge thereof, accommodating a laterally projecting rib 23, on the upper edge of the key bricks 13. The inner surface of the bricks 13, are likewise inclined and recessed to accommodate the lateral rib 24, on the key bricks 14. The row of bricks 15, 10 differ somewhat in that their upper edges are above the contour line defined by the key bricks 13, 14, and the outer incline of the bricks is continued upwardly thereby providing an overhanging or projecting portion 25, which overlies the key bricks 14. The upper surface of the rows, 15, 16, 17 of the bricks is preferably in a horizontal plane. All the bricks are tapered and are maintained in proper relation by the action of 20 the key bricks 13, 14.

In order to provide for expansion following the heating of the roof, I locate wood strips 26, 27, 28, between the rows 12, 13, 14, 15 of bricks, these being applied when the 30 roof is built. The intense heat of the furnace will, however, cause these strips to be destroyed and, therefore, permit the necessary expansion. Should any of the strips burn out before others thereof, the key bricks 35 cannot be displaced vertically as they will be retained by the interengaging ribs and recesses.

A furnace roof constructed in accordance with my invention will be found to retain its 40 shape and efficiency for long periods of time. When, however, extensive repairs become necessary it may be very quickly removed and replaced with another roof.

While I have shown the invention in association with a roof for a circular furnace, 45 many of the advantages thereof will accrue in roofs having different shapes, and I do not wish to be limited to the exact form shown herein.

50 I claim:

1. A furnace roof comprising abutments, a central roof portion, and expansion joint roof portions including destructible spacing members between the central roof portion 55 and the abutments.

2. A furnace roof comprising a central roof portion, an abutment surrounding said central roof portion, and an expansion joint

portion including destructible spacing material between the abutment and the central 60 roof portion.

3. A furnace roof comprising opposite abutments, a central flat roof portion having openings therethrough for the introduction of electrodes, and expansion joint roof 65 portions interposed between the respective abutments and the central roof portion, each expansion joint roof portion including two rows of bricks, adjacent bricks of the rows having a socket and projection supporting 70 inter-engagement, and a compressible filler between said bricks.

4. A furnace roof comprising a ring, a skewback within and supported by the ring, an internal flange carried by the ring and 75 disposed on top of the skewback, a central roof portion, and an expansion joint roof portion between the skewback and the central roof portion, said expansion roof portion including two rows of bricks, there being a socket and projection inter-fitting support between the rows of bricks and also between the outer row of bricks and the skewback, and a compressible filler between the rows of bricks and also between the outer 80 row of bricks and the skewback.

5. A furnace roof comprising abutments, a central roof portion between the abutments, and an expansion joint roof portion between the central roof portion and each 90 abutment, the expansion joint roof portion including rows of bricks, one row of bricks having a groove at the top thereof, an adjacent row of bricks having a tongue fitting in the groove and supporting said adjacent 95 row on said one row, and a compressible filler between said rows of bricks.

6. A furnace roof comprising a ring, a skewback within and supported by the ring, a central roof portion, and an expansion 100 joint roof portion including destructible spacers between the skewback and the central roof portion.

7. A furnace roof comprising a ring, a skewback within and supported by the ring, 105 an internal flange carried by the ring and disposed on top of the skewback, a central roof portion, and an expansion joint roof portion between the skewback and the central roof portion.

Signed at Anniston, Alabama, this 19th day of February, A. D. 1917.

PATRICK JOSEPH GRIFFIN.
